UNITED STATES PATENT OFFICE.

ALLAN M. HOLTON, OF GLENDALE, CALIFORNIA.

DESIGN FOR A DOLL.

Application filed November 4, 1924. Serial No. 11,288. Term of patent 7 years.

To all whom it may concern:

Be it known that I, ALLAN M. HOLTON, a citizen of the United States, residing at Glendale, in the county of Los Angeles and State of California, have invented a new, original, and ornamental Design for Doll, of which the following is a specification, reference being had to the accompanying drawing, forming part thereof.

The figure is a perspective view of the doll.

I claim:

The ornamental design for a doll, as shown.

ALLAN M. HOLTON.
